UNITED STATES PATENT OFFICE.

ROBERT IREDELL, OF AKRON, OHIO, ASSIGNOR TO THE GENERAL TIRE AND RUBBER COMPANY, OF AKRON, OHIO, A CORPORATION OF OHIO.

DESIGN FOR A TIRE-CASING.

6,282.

Specification for Design.

Patented Sept. 14, 1920.

Application filed January 26, 1920. Serial No. 354,268. Term of patent 14 years.

To all whom it may concern:

Be it known that I, ROBERT IREDELL, a citizen of the United States, residing at 875 Ardmore Ave., in the city of Akron and county of Summit and State of Ohio, have invented a new, original, and ornamental Design for Tire-Casings, of which the following is a specification, reference being had to the accompanying drawings, forming a part thereof.

In said drawing, the figure is a perspective view of a tire casing showing my new design.

I claim:

The ornamental design for a tire casing as shown.

ROBERT IREDELL.
